United States Patent Office

Des. 185,921

Patented Aug. 18, 1959

185,921

COMBINATION WINDSHIELD SCRAPER, RADIATOR CAP REMOVER, BOTTLE OPENER, AND RULER

Robert B. Draper, Merryfield, Va.

Application November 3, 1958, Serial No. 53,238

Term of patent 3½ years

(Cl. D52—1)

FIG. 1

FIG. 2

FIG. 3

Fig. 1 is a top perspective view of a combination windshield scraper, radiator cap remover, bottle opener and ruler, showing my new design;

Fig. 2 is a side elevation; and

Fig. 3 is a bottom plan view thereof.

I claim:

The ornamental design for a combination windshield scraper, radiator cap remover, bottle opener, and ruler, as shown.
